UNITED STATES PATENT OFFICE.

SAMUEL SANDERS, OF LEAVENWORTH, KANSAS.

DESIGN FOR A KITCHEN-CABINET.

SPECIFICATION forming part of Design No. 28,767, dated May 31, 1898.

Application filed April 23, 1898. Serial No. 678,677. Term of patent 7 years.

To all whom it may concern:

Be it known that I, SAMUEL SANDERS, of Leavenworth, in the county of Leavenworth and State of Kansas, have invented and produced a new and original Design for a Kitchen-Cabinet, of which the following is a full, clear, and exact description.

Reference is to be had to the accompanying drawing, forming a part of this specification, in which the figure is a perspective view of a kitchen-cabinet showing my design.

The design consists of a base having a paneled front A, flanked by posts B, and having ornamental legs C appearing at the said front, the upper portions of the legs appearing with a band-like vertical connection D, and a superimposed horizontal top E below and in front of a top F. On the face of the band-like connection D appears the drawer-like figure D'. The side of the base of the cabinet is ornamented with a series of drawer-like figures G, and from the rear portion of the base rises a casing having the front edges H² of its sides H' curved upwardly and rearwardly, giving the sides H' a reduced effect at the upper portion. Between the sides extend the horizontal shelf-like figures I, a ver-

tical base J extending from one side H' to the other. An ornamental top K surmounts the upper end of the casing H, and below this top K appears the band-like figure L, terminating at its ends under the front edges H² of the side H. An ornamental handle L' projects from the band L at the middle thereof. The back N of the casing H appears in different-formed panels N N' N², the shelf-like figures I and the sides H forming the boundary for the said panels.

The essential features of my design consist in the base and the casing H, rising from the base at the rear portion thereof, and with the front edges H² of the sides H' curved, the base having its front appearing with side posts and ornamental legs connected by a vertical band, and a horizontal top leading to a step-like top F of the base, the said top appearing in front of the lower portion of the casing H.

I claim—

The design for a kitchen-cabinet, as herein shown and described.

SAMUEL SANDERS.
